UNITED STATES PATENT OFFICE.

JOHN H. CARR, OF EVERETT, MASSACHUSETTS.

SLOW-CLOSING VALVE.

1,162,134.

Specification of Letters Patent. Patented Nov. 30, 1915.

Application filed October 15, 1915. Serial No. 56,031.

To all whom it may concern:

Be it known that I, JOHN H. CARR, a citizen of the United States, and resident of Everett, in the county of Middlesex and 5 State of Massachusetts, have invented certain new and useful Improvements in Slow-Closing Valves, of which the following is a specification.

The object of the present invention is to 10 provide an improved slow-closing valve suitable for controlling the discharge of water from flushing tanks.

It is desirable that the outlet valve of a 15 flushing tank be opened quickly and held open automatically for a sufficient length of time to permit the discharge of all or nearly all the water in the tank, and to close automatically when the desired volume of water has been discharged.

20 The valve which embodies the present invention includes co-operative telescoping members which together form a dashpot, into which dashpot water is admitted from the tank. The closing movement of the 25 valve is retarded by restricting the escape of water from the dashpot. I am aware that the use of a dashpot for this purpose is not broadly new, U. S. Patent to Smith, 391,659, showing a flushing valve including a dashpot for this purpose. In the Smith patent 30 above mentioned the admission of water to the chamber of the dashpot is controlled to some extent by a check valve, said check valve being arranged to close as the main 35 valve moves toward its seat, to retard the escape of water from the dashpot. A check valve for this purpose is sometimes unsatisfactory because it may stick, and if it fails to close when it should the closing movement 40 of the main valve will be too rapid to permit the discharge of the necessary volume of water from the tank. One cause of sticking is due to the accumulation of slime and other dirt deposited in the valve mechanism by the 45 water, and in order to overcome the difficulty it is necessary to take the valve apart and clean it. The benefit of cleaning is only temporary at best because more slime or other dirt will continue to accumulate as water is circulated through the tank.

50 My present invention embodies other means than a check valve for controlling the admission of water to and the discharge of water from the dashpot, said means being positive in action, or as nearly positive as is 55 consistent with the fact that the closing

movement of the main valve is due to gravity. The main valve is made sufficiently heavy to insure closing movement, and its weight is utilized to effect the control of the 60 water which is admitted to and discharged from the dashpot.

Of the accompanying drawings which 65 illustrate one form in which the present invention may be embodied: Figure 1 represents a side elevation of my improved flushing valve as applied to a flushing tank, the latter being shown in section. Fig. 2 represents a vertical section, on a larger scale, of the valve structure. Fig. 3 represents an 70 elevation of the structure within the range of line 3—3 of Fig. 2. Fig. 4 represents a top plan view of the structure shown by Fig. 2.

The same reference characters indicate the 75 same parts wherever they occur.

A portion of a flushing tank is indicated at 10 in Fig. 1. The valve seat member of a flushing valve is indicated at 11, and the flushing valve is indicated at 12. The valve 80 and valve-seat member are so arranged that the valve will open as it moves upwardly. A lug 13 at the upper end of the valve is connected with the usual operating lever (not shown) by suitable means which will 85 enable the valve to turn to a limited extent about a vertical axis. Such connecting means in the present instance includes a lifting rod 14 the lower end of which is hooked through the lug 13. The valve is 90 made sufficiently heavy to close firmly and is provided with an annular disk 15 of relatively soft material such as leather, said disk being arranged to engage the annular seat 16 formed upon the member 11. 95

The upper portion of the valve 12 is in the form of a sleeve, but is closed at the top. The internal surface of the sleeve portion is cylindrical, and it is adapted to slide on a tubular guiding member 17. This guiding 100 member is open at its upper end but closed at its lower end, and in conjunction with the valve it forms a chamber 18 which is closed excepting as hereinafter specified. The guiding member 17 rests upon a support 19 105 which in the present instance is a bridge portion forming an integral part of the valve-seat member 11 and bridging across the discharge passage 20 of said member. The guiding member 17 is provided with a 110 stem 21 which extends through the bridge portion 19 and is provided with a nut 22.

The hole 23 through which the stem extends is preferably larger than the stem, for the purpose of enabling the guiding member to tilt to a limited extent so that the main valve may seat accurately.

For the purpose of admitting water from the tank into the chamber 18 of the dashpot the tubular member 17 is provided with a slot 24 and the sleeve portion of the valve is provided with a port 25. The port normally registers with the slot 24, and it is only during the closing movement of the valve that the port is out of register with the slot. In order to cause the port and slot to permit the admission of water to the chamber 18 and to prevent the discharge of water therefrom the slot is made crooked. In the present instance the lower portion of the slot is parallel to the axis of the tubular member and the upper portion 24' is substantially helical. The fundamental principle of the invention does not necessitate this specific form of slot, as will be understood after further description, for it would be within the scope of the invention to have the slot helical throughout its length. The chief consideration, so far as the slot is concerned, is that the upper end of the slot shall be out of vertical alinement with the lower end of the slot, to the end that the port 25 in descending vertically from a position in register with the upper end of the slot will pass out of register with the slot and remain out of register throughout the greater portion of the closing movement of the valve. It is desirable, however, that the port 25 remain in register with the slot throughout the upward movement of the valve in order to maintain open communication between the tank and the chamber 18 to admit water to the latter so long as the effective area of the chamber increases.

In order to maintain the port in register with the slot throughout the upward movement of the valve, I provide means adapted to turn the valve in one direction, and in order to move the port back into register with the slot when the valve is closed I provide means for turning the valve in the opposite direction, said means enabling the valve to traverse a substantial proportion of its closing movement while the port is out of register. In the present instance the means for this purpose comprise cam surfaces formed upon the valve and a suitable fixture arranged to coact with such surfaces. The cam surface indicated at 26 is the one which acts during the upward movement of the valve to cause the port to follow the helical portion 24' of the slot. The cam surface indicated at 27 is the one which causes the port to move back into register with the lower end of the slot while the valve is traversing the latter portion of its closing movement. These cam surfaces are provided by forming ribs or flanges

28 and 29 upon the exterior of the sleeve portion of the valve. The fixture which co-operates with these cam surfaces is indicated at 30. This fixture may be mounted in any desirable manner so long as it bears the desired relation to the valve. In the present instance the member 30 is made an integral part of a collar 31, and the latter is rigidly secured to a standpipe 32 which in valves of this kind is usually provided to take care of overflow from the tank. The collar 31 is bored and tapped and provided with a set-screw 33 whereby it may be set up tightly on the pipe, and it is provided with a dowel 37 which slips into a socket 38 to insure the desired co-operation of the port 25 and slot 24.

Figs. 1 and 2 show the valve in its closed position, and they also show the port 25 as being in register with the lower end of the slot, thus maintaining open communication between the tank and the chamber 18 of the dashpot. As the valve is lifted the port will normally follow the straight lower portion of the slot, but as the port reaches the curved portion of the slot the cam surface 26 engages the fixture 30; and if the upward movement of the valve be continued to carry the port as high as the upper end of the slot, the cam surface 26 traversing the fixture 30 will cause the valve to turn so that the port 25 will follow the crooked or offset portion 24' of the slot. Consequently as the effective area of the chamber 18 increases with the upward movement of the valve, open communication between said chamber and said tank will be maintained so that water may flow into the chamber to keep the latter filled. When the valve is raised to its highest position the port will occupy the position indicated by dotted lines at 25' in Fig. 2. Now if the valve be released it will descend under the force of gravity, and the first part of its descent will not be accompanied by any rotative movement. The port will therefore traverse the path indicated by the series of arrows in Fig. 2. Before the valve has traversed a substantial part of its downward movement the port will have moved out of register with the slot, thereby closing the chamber 18 so far as this means of escape is concerned. It is necessary, however, to permit the water in the chamber 18 to escape slowly, and for this purpose the valve is provided with a restricted outlet 34, 35 (Fig. 2) which is controlled by a screw 36. It is possible that a very small proportion of water will also escape between the telescoping surfaces of the valve and guiding tube 17, but this would probably be negligible. In any event, as the water escapes from the chamber 18 through the restricted outlet or outlets the valve descends at a speed commensurate with such escape; but before the valve reaches its seat the cam surface 27 moves into contact with the fixture 30 and as it

traverses said fixture it causes the valve to turn in the opposite direction, thereby moving the port back into register with the lower portion of the slot.

5 The actual registration of the port with the slot begins before the valve quite reaches its seat, and the water in the chamber 18 is thus permitted to escape more rapidly so that the last stage of downward movement 10 of the valve will be accelerated. The valve will therefore engage its seat with a forcible impact which is desirable for this purpose. Such acceleration and the consequent impact may be amplified by giving greater relief to 15 the dashpot, and I have shown ports 39 and 40 for this purpose. These ports register when the valve is in its closed or initial position, but move out of register as the valve rises. They remain out of register until the 20 valve in its downward travel is comparatively near its seat, and the rotative movement as caused by cam 27 puts them in register at about the same time that port 25 moves back into register with slot 24.

25 It is to be noted that the opening and closing of the passageway through the port 25 and slot 24 is caused by elements which act positively, the qualification "positively" being used with due regard to the fact that 30 the descent of the valve is due solely to the force of gravity. However, if the valve is moved vertically its rotative movement would in every case be positive, and there would be no opportunity for the port and 35 valve to fail to move into and out of register provided the necessary vertical movements of the valve occurred as intended. The wiping action of the sleeve portion of the valve upon the tubular member 17 tends 40 to keep the telescoping surfaces free from slime or other dirt which might otherwise accumulate on them, and when the device has once been installed with the parts correctly adjusted there would be no possibility 45 of failure of operation.

It would be within the scope of the present invention to interchange the slot 24 and port 25, that is, to form the port in the telescoping member 17 and the slot in the telescoping member 12. It would also be within 50 the scope of the invention to form a series of ports instead of the elongated slot 24, for the effect would be substantially the same. The invention contemplates broadly any 55 means capable of turning one telescoping member relatively to the other as the valve rises and falls; to control the admission of water to and the discharge of water from

the dashpot chamber substantially as described.

60

I claim—

1. The combination with a valve, of a dashpot comprising two principal elements one of which is movable longitudinally with relation to the other, and one of which is 65 capable of rotative movement relatively to the other, said longitudinally movable element being so movable with said valve as the latter opens and closes, said two principal elements of said dashpot having co-operative openings arranged to be moved into and out of register by turning said rotative element, and means arranged to turn 70 said rotative element in consequence of operating said valve, to register and unregister 75 said openings for the purpose stated.

2. The combination with a valve, of two hollow cylindric telescoping elements forming a dashpot, one of said elements being movable longitudinally as said valve opens 80 and closes, and means arranged to turn one of said elements relatively to the other in consequence of operating said valve, said elements having co-operative openings arranged to be moved into and out of register 85 with each other by such turning of said one of said elements.

3. The combination with a valve, of two hollow cylindric telescoping elements forming a dashpot, one of said elements being 90 united with said valve so as to move longitudinally as the valve opens and closes, said elements having openings arranged to be moved into and out of register with each other by relative rotative movement of said 95 elements, and means arranged to turn said one of said elements in consequence of operating said valve, to register and unregister said openings for the purpose stated.

4. The combination with a valve, of two 100 hollow cylindric telescoping elements forming a dashpot, the outer one of said elements being united with said valve so as to move longitudinally as the valve opens and closes, one of said elements having a substantially 105 helical slot and the other having a port arranged to register with said slot, and means arranged to turn said outer element in consequence of longitudinal movement thereof, to cause said port to follow said slot as the 110 valve opens, said outer element being movable to unregister said slot and port as the valve traverses its return movement.

In testimony whereof I have affixed my signature.

JOHN H. CARR.
